UNITED STATES PATENT OFFICE

LODIAS J. DUGAS, OF CHICAGO, ILLINOIS, ASSIGNOR TO DU-GAS FIRE EXTINGUISHER CORPORATION, OF NEW YORK, N. Y., A CORPORATION OF DELAWARE

FIRE-EXTINGUISHING MATERIAL

No Drawing.

Application filed September 19, 1927. Serial No. 230,621.

This invention relates to fire extinguishing material and to a method of using such material in the extinction of fires.

In the usual type of chemical fire extinguisher, a liquid is employed, either of the organic non-combustible class such as carbon tetrachloride, or a solution of sodium bicarbonate and an acid adapted when brought into contact with the bicarbonate solution to liberate carbon dioxide gas. In either case, fire extinguishers of the liquid containing type possess a serious disadvantage, that in extremely cold weather the liquid or solution is liable to freeze unless protected from the cold. There is the further objection to most types of liquid fire extinguishers that the liquid, especially acid and water, does more damage in many small fires than the fire itself.

It is therefore an object of this invention to provide fire extinguishing material in solid dry form, adapted to be applied directly without the use of liquids to the conflagration area.

It is a further object of this invention to provide a method of applying a dry fire extinguishing powder to a fire by delivering the same in a high pressure stream of a non-combustible gas.

Other and further important objects of this invention will be apparent from the following description and appended claims.

I have now found that sodium bicarbonate in dry form makes a very efficient fire extinguishing material if applied directly to the burning objects. Especially is this true of oil fires, where water is worse than useless since it simply tends to spread the fire. Sodium bicarbonate on the other hand has a twofold advantage in fighting oil fires. In the first place, the heat of the fire decomposes the bicarbonate to liberate carbon dioxide which forms a blanket around the fire and eventually smothers it. In the second place, the sodium carbonate formed as a result of the decomposition of the bicarbonate, if sufficiently heated, fuses over the surface of the oil to form a non-combustible film. In the case of fires caused by electric arc, the sodium carbonate tends to fuse over the sur-

face of the conductors to form an insulating film, thus resulting in the smothering of the arc.

I have further found that sodium bicarbonate may be satisfactorily mixed with certain other ingredients adapted to prevent the bicarbonate from caking and also adapted to form a flux over the burning material. Among these other ingredients may be mentioned fillers, such as infusorial earth, asbestos dust, silica and ash, and fusible materials, such as sodium borate, calcium chloride and sodium chloride. As an example of a satisfactory composition of my fire extinguishing material, the following analysis is given:

	Per cent
Sodium bicarbonate	65
Calcium chloride	15
Sodium borate	10 70
Silica	2
Ash	3
Sodium chloride	5

In fighting fires, this fire extinguishing material is preferably used in connection with my fire extinguisher shown in my copending application, Serial No. 132,179, filed August 28, 1926. In that application there is shown a cylindrical container adapted to be filled with the dry fire extinguishing material and having means for admitting thereto a gas under high pressure for discharging powder through a nozzle connected with the container. I prefer to use nitrogen as the carrier for the fire extinguishing powder. By this means a high pressure stream of nitrogen carrying the extinguishing powder may be delivered against a burning object from a considerable distance and the fire put out in a very short time due to the combined action of the sodium bicarbonate and inert nitrogen gas.

It will be apparent that my fire extinguishing material has none of the disadvantages of the liquid chemicals commonly used and is therefore much more satisfactory for fighting fires. It should be further noted that no water is necessary in the application of the extinguishing powder and that therefore there is no attendant damage such as is so

often the case in fires in which large quantities of water are used.

I am aware that many changes may be made, and numerous details of the process may be varied through a wide range without departing from the principles of this invention, and I therefore do not purpose limiting the patent granted hereon, otherwise than necessitated by the prior art.

10 I claim as my invention:

1. Fire extinguishing material having approximately the following composition and adapted to be applied in dry form:

	Per cent
15 Sodium bicarbonate	65
Calcium chloride	15
Sodium borate	10
Silica	2
20 Ash	3
Sodium chloride	5

2. Fire extinguishing material comprised largely of dry sodium bicarbonate, and containing relatively smaller quantities of calcium chloride, sodium borate, sodium chloride, and a filler.

In testimony whereof I have hereunto subscribed my name at Chicago, Cook County, Illinois.

30 LODIAS J. DUGAS.
